Primary Examiner — Karen E Eldridge Powers(74) *Attorney, Agent, or Firm* — Grossman, Tucker, Perreault & Pfleger PLLC(57) **CLAIM**

The ornamental design for a brush roll, as shown and described.

DESCRIPTION

FIG. 1 is a first perspective view of a first end of the brush roll;

FIG. 2 is a second perspective view of the first end thereof;

FIG. 3 is a first perspective view of a second end thereof;

FIG. 4 is a second perspective view of the second end thereof;

FIG. 5 is a first side elevation view thereof;

FIG. 6 is a second side elevation view thereof;

FIG. 7 is a third side elevation view thereof;

FIG. 8 is a fourth side elevation view thereof;

FIG. 9 is a plan view of the second end thereof; and,

FIG. 10 is a plan view of the first end thereof.

The broken lines, and the features shown by the use of broken lines, form no part of the claimed design.

1 Claim, 8 Drawing Sheets(56)
